M. C. MILLER,
KNITTING MACHINE,
APPLICATION FILED JULY 20, 1916.

1,245,007.

Patented Oct. 30, 1917.

UNITED STATES PATENT OFFICE.

MAX C. MILLER, OF CUMBERLAND HILL, RHODE ISLAND, ASSIGNOR TO JENCKES
KNITTING MACHINE COMPANY, OF PAWTUCKET, RHODE ISLAND, A CORPORA-
TION OF RHODE ISLAND.

KNITTING-MACHINE.

1,245,007.

Specification of Letters Patent. Patented Oct. 30, 1917.

Application filed July 20, 1916. Serial No. 110,394.

To all whom it may concern:

Be it known that I, MAX C. MILLER, a subject of the Emperor of Germany, residing at Cumberland Hill, in the county of Cumberland and State of Rhode Island, have invented certain new and useful Improvements in Knitting-Machines; and I do hereby declare the following to be a full, clear, and exact description of the invention, such as will enable others skilled in the art to which it appertains to make and use the same.

The invention relates to knitting machines having independently-operated spring needles.

An object of the invention is to secure an effective wrapping of the yarn about the needles of a circular machine between the yarn guide from which the yarn leads directly to the needles and the knock-over point where the new loop is drawn through the old loop and the old loop cast off. To this end the stitch cams are shaped to draw down the needles in two stages, with a substantial dwell between them, thus forming a two-stage knitting wave with an intermediate dwell. This enables the yarn guide to be located in advance of the dwell and at a sufficient distance from the knock-over point to secure a wrap of the yarn about the needles from the knock-over point to the yarn taking point without requiring an excessive vertical movement of the needles.

A further object of the invention is to provide means for evening the old loops on the needles just before the new loops are drawn and the old loops cast off, thus securing a uniform fabric and permitting a tighter stitch to be formed. For this purpose a two-stage knitting wave is so formed that the dwell in the downward movement of the needles occurs after the beards have been pressed and have entered the old loops to such an extent that the loops on the series of needles in the dwell encircle the springy parts of the beards. The spring of the beards will therefore evenly distribute the yarn among the loops about these needles before they reach the second stage of the knitting wave, so that the stitches will be uniform and may be knit tighter without danger of breaking or cutting the yarn.

The different features of the invention will be understood from an inspection of the

accompanying drawings and the following detailed description of the mechanism illustrated therein.

In the drawings, Figure 1 is a vertical sectional view indicating so much of a circular spring-needle machine as is necessary to illustrate the application of the preferred form of the present invention thereto; Fig. 2 is a similar view taken through the point where the needle positioning presser engages the backs of the needles; Fig. 3 is a plan view showing the parts illustrated in Figs. 1 and 2; Fig. 4 is a diagrammatic view showing the form of the knitting cam and the two-stage wave which is formed in the needles by the cam; and Fig. 5 is a detail view indicating the position of the loops on the needles and the dwell in the knitting wave.

In the drawings the invention is shown embodied in a circular machine. The needle cylinder, which is indicated at 1, is provided with the usual vertical needle grooves within which the spring-needles 2 are mounted to reciprocate vertically. The needles may be reciprocated by knitting cams arranged about the needle cylinder in any usual and well-known manner. The upper end of the needle cylinder carries a web holder ring 3 provided with radial grooves for the web holders 4, which may be operated in the usual manner by a cam ring 5.

The means for closing the beards of the needles comprises a presser plate in the form of a ring 6 which surrounds the needles, and a coöperating presser in the form of a small disk 7 which engages the backs of the needles at the pressing point and presses them outward, so that the beards engage and are closed by the presser ring 6. The ring is mounted upon the web holder ring 3 so that it remains in fixed relation to the needles. The presser disk is mounted to rotate freely on a screw 8 secured in the free end of a supporting arm 9 which is pivotally supported on a pivot screw 10 and is pressed in a direction to force the disk against the backs of the needles by a spring 11. Assuming that the travel of the needle with relation to the stitch cams, due to the rotation of either the needle cylinder or cam cylinder, is in the direction of the arrow, Fig. 3, the supporting arm for the presser disk is so mounted that when it yields it

will swing obliquely away from the needles in the direction of their travel, thus relieving any undue pressure which might otherwise injure or break the needles or deflect them laterally. The yarn indicated at *y* leads from a yarn guide 12 directly to the needles, and in order that it may enter the hooks of the needles as the needles are drawn down, it should lie snugly against the fronts 10 of the needles at the point where the beard passes the yarn. To insure the proper engagement of the yarn with the needles at this point, a needle positioning presser 13 is arranged to engage the backs of the needles 15 and preferably to deflect them outward at the point where the beards pass the yarn, which for convenience may be termed the yarn taking point. As shown, this presser consists of an arm pivoted on the screw 10 above the arm 9, and pressed against the backs of the needles by a spring 14. The forward movement of the presser is limited by an adjusting stop screw 15 mounted on the presser and arranged to engage a fixed 20 stop 16. As the needle travels along the presser, any needle which may be bent inward out of alignment with the adjacent needles, or may be out of proper position to take the yarn, will be pressed outward into 25 correct yarn taking position, so that the yarn which wraps around the needles will lie against the outer sides of these needles which are passing the yarn taking point. This will insure the passage of the yarn under the beards and into the hooks of the 30 needles.

To even the loops on the needles before they reach the knock-over point, and to secure an adequate wrap of the yarn about 40 the needles, in case the yarn is fed directly to the needles, the knitting cams are shaped to form a two-stage knitting wave with an intermediate dwell, as indicated diagrammatically in Fig. 4, the general shape of the 45 knitting cam being indicated by the dotted lines which also indicate the paths of movement of the upper ends of the needles and the lower ends of the beards. During the first stage 17 of the knitting wave the yarn 50 is taken by the needles, and the beards are pressed and enter the old loops which are supported by the web holders. After the needles have been moved downward, so that the loops surrounding the needles are part 55 way up the beards, as indicated in Fig. 5, they pass into the dwell 18 of the knitting wave, and as they travel along this part of the wave the outward spring of the beards tends to evenly distribute the yarn among 60 the loops about the needles. Just before the needles reach the knock-over point they pass down the second stage 19 of the wave, draw-

ing new loops through the old loops which are cast off or knocked over the upper ends of the needles, so that the needles rise through the new loops.

While the invention has been shown as embodied in a circular machine, it will be understood that certain features of the invention are not confined in their application to circular machines, but may be embodied with advantage in other types of spring-needle machines. It will also be understood that the specific construction and arrangement of parts shown and described is not essential to the broader features of the invention, but may be varied or modified as found desirable or best suited to the construction of the machine in which the invention is to be embodied. It will also be understood that the invention may be embodied in machines in which the needle cylinder rotates, or in which the cam cylinder rotates, and also that certain features of the invention may be embodied in machines provided with yarn measuring sinkers, as well as in machines in which the yarn is fed directly to the needles.

Having explained the nature and object of the invention, and specifically described one form of mechanism in which it may be embodied, what is claimed is:—

1. A knitting machine, having, in combination, independently-operated spring-needles, means for forming a two-stage knitting wave in the needles with an intermediate dwell, and means for feeding the yarn directly to the needles without sinking and pressing the beards during the first stage and for casting off the old loops during the last stage, the pressing being terminated while the old loops are on the spring part of the beards.

2. A knitting machine, having, in combination, independently-operated spring-needles, means for forming a two-stage knitting wave in the needles with an intermediate dwell, the loops on the series of needles in the dwell embracing the spring part of the beards and means for feeding yarn directly to the needles without sinking, and for terminating the pressing while the old loops are on the spring part of the beards.

3. A knitting machine, having, in combination, independently-operated spring-needles, means for forming a two-stage knitting wave in the needles with an intermediate dwell, and means for feeding the yarn directly to the needles during the first stage without sinking, and for terminating the pressing while the old loops are on the spring part of the beards.

MAX C. MILLER.
